GRAPPLING OR PULLING TOOL

Alton T. Danielson, North St. Paul, Minn.

Application March 30, 1940, Serial No. 327,041

3 Claims. (Cl. 294—118)

This invention relates to a grappling or lifting tool. It is desirable in such a tool to have gripping jaws arranged to exert great pressure on the object grasped, which pressure preferably increases with the pulling effort or force. It is also desirable to have a grappling tool having opposed jaws mounted to swing so that they can come into parallel or substantially parallel relation when an object is grasped. It is also desirable to have a grappling tool that can be moved vertically along the side of a wall or surface to engage an object between the jaws thereof.

It is an object of this invention, therefore, to provide a simple and efficient grappling tool having gripping jaws, said tool being so arranged that the gripping pressure increases with the lifting or pulling force exerted on said tool.

It is a further object of the invention to provide a grappling tool comprising a pair of levers hinged together adjacent their ends, said levers having projections extending laterally at the same side thereof to which are connected swinging jaws, said jaws thus being offset at one side of said levers.

It is more specifically an object of the invention to provide a pair of levers pivoted adjacent one end having flanges projecting laterally therefrom at said ends, lugs extending vertically from said flanges and jaws pivoted between said lugs and said sides, said jaws having opposed corrugated faces together with links connecting the other ends of said levers, which links are pivotally connected to a member adapted to be connected to a lifting means.

These and other objects and advantages of the invention will be fully set forth in the following description made in connection with the accompanying drawing in which like reference characters refer to similar parts throughout the several views and in which:

Fig. 1 is a perspective view largely in side elevation of the tool;

Fig. 2 is a vertical section taken on line 2—2 of Fig. 1 as indicated by the arrows;

Fig. 3 is a horizontal section taken on line 3—3 of Fig. 1 as indicated by the arrows; and

Fig. 4 is a perspective view of one of the jaws used.

Referring to the drawing, a lever 10 is shown and while this lever could be variously formed, in the embodiment of the invention illustrated it is shown as made of a substantially flat bar rectangular in transverse cross section. One end of the lever is increased in thickness and the same has a slot 10a extending therethrough. Lever 10

has a flange 10b extending laterally from one flat side thereof at its lower end. A flange-like lug 10c extends perpendicularly to flange 10b substantially parallel to the adjacent flat side of said lever and another flange 10d extends between lug 10c and the adjacent side of lever 10. Another lever 11 is provided, also illustrated as formed from a substantially flat bar rectangular in transverse cross section, said lever 11 extending through slot 10a. Levers 10 and 11 are pivoted together by a countersunk pivot rivet 12. Lever 11 at its lower end has a flange 11b projecting from one side thereof in the same direction as does flange 10b. A flange-like lug 11c extends perpendicularly to flange 11b at the outer side of flange 11b and a flange 11d extends perpendicularly to flange 11b between lug 11c and the adjacent side of lever 11, said flange being extended upwardly in tapered formation as a rib. As shown flanges 10c and 11c are in substantially the same vertical plane. Levers 10 and 11 have pivoted thereto respectively jaws 13 and 14. Jaw 13 has a flat rectangular plate-like portion from one side of which projects a lug 13a disposed between lug 11c and the adjacent side of lever 11, the same being pivotally connected to lever 11 by the pivot rivet 15. Pivot rivet 15 is countersunk at the outer side of lug 11c. Jaw 13 has an outer gripping face 13b shown as corrugated and having V-shaped ribs extending substantially horizontally therein. Jaw 14 has a lug 14a disposed between lug 10c and the adjacent side of lever 10 and is connected to said lever by a pivot rivet 16. Pivot rivet 16 is countersunk at the outer side of lug 10c. Jaw 14 also has a rectangular plate-like portion having a gripping surface or face 14b illustrated as being formed with substantially horizontally V-shaped ribs. Levers 10 and 11 have pivotally connected thereto at their upper ends respectively links 17 and 18, said links having their other ends in alignment and disposed between the arms of a yoke member 19. Links 17 and 18 are pivotally connected to the lower ends of said arms by a pivot rivet 20. A filling washer 21 is disposed on rivet 20 between links 17 and 18. The yoke member 19 is of inverted U-shape and its bight portion is disposed in a ring 22 connected to the lower end of a chain 23, which chain will be connected to some suitable pulling means.

In operation, when an object is to be engaged to be lifted the tool will be lowered so that the jaws 13 and 14 are disposed at either side of said object. Upon lifting of chain 23 links 17 and 18 will be lifted and this will swing levers 10 and 11

toward each other until jaws 13 and 14 engage the said object. Said jaws 13 and 14 can swing so that the opposed corrugated surfaces of the jaws will come into substantially parallel relation at either side of a plate, pin or similar object to be gripped. Continued lifting or pulling upon member 23 will tend to move jaws 13 and 14 toward each other and increase the gripping effect. The chain 23 will be lifted until the object gripped is lifted or raised as desired. The lugs 10c and 11c form stops at their adjacent edges which are engaged by the rear sides of the jaws 13 and 14.

From the above description it will be seen that I have provided a very simple and efficient grappling tool. By having the jaws 13 and 14 offset at one side of the levers the tool can be lowered along the side of a wall or surface so that the jaws can engage with a pin or other object adjacent said surface. This is often important in pulling loose pins or plates used in concrete forms or other similar work.

The tool is very rugged in construction and can be used to exert great force upon an object which is to be pulled or lifted. The device has been amply demonstrated in actual practice and found to be very successful and efficient.

It will, of course, be understood that various changes may be made in the form, details, arrangement and proportions of the parts, without departing from the scope of applicant's invention, which generally stated, consists in a device capable of carrying out the objects above set forth, in the parts and combinations of parts disclosed and defined in the appended claims.

What is claimed is:

1. A grappling tool having in combination, a pair of levers connected by a pivot adjacent their ends, said levers having flanges projecting therefrom respectively at the same sides thereof and substantially parallel to the axis of said pivot, lugs upstanding from said flanges respectively, jaws pivoted respectively to said lugs above said flanges about axes extending parallel to the axis of said pivot, said jaws having opposed corrugated faces adapted to swing into parallel relation when an object is grappled, said flanges respectively forming stops for said jaws, links connected at one end respectively to

the opposite ends of said levers and means pivotally connected to the other ends of said links adapted to receive a support for said tool adapted to be lifted.

- 5 2. A grappling tool having in combination, a pair of levers connected by a pivot adjacent their ends and having projections extending laterally at the same sides thereof respectively so as to have portions disposed respectively at 10 said side, a jaw having a portion pivoted to each lever in alignment with said projection and about a pivot extending parallel to said first mentioned pivot, said jaws having gripping surfaces disposed in single planes respectively and 15 extending to the edges of said jaws and extending to one side of said levers so that no part of said tool extends beyond the edges of said jaws at said side thereof, said gripping surfaces being adapted to swing into substantially parallel relation at opposite sides of an object gripped 20 whereby said jaws can be disposed with their sides against a vertical surface and an object close to said surface engaged by said gripping surface without the rest of said tool engaging said surface.
- 25 3. A grappling tool having in combination, a pair of levers connected by a pivot adjacent their ends, said levers having substantially flat sides and each having a flange projecting laterally at the bottom thereof from said flat sides, 30 said flanges projecting in the same direction, a flange-like lug extending upwardly from said flange on each of said levers, said lugs being disposed in substantially the same plane, a jaw 35 having a lug pivoted between said lug and said flange on each of said levers about a pivot the axis of which is parallel to the axis of said pivot, said jaws having gripping surfaces thus disposed at one side of said levers, said gripping surfaces 40 being disposed in single planes respectively having sides substantially aligned with one side of said levers so that no part of said tool projects beyond said side whereby said jaws can be disposed with the said sides adjacent a vertical surface and an object close to said surface engaged by said jaws without the rest of said tool 45 engaging said surface.

ALTON T. DANIELSON.
